UNITED STATES PATENT OFFICE

FRANK M. ASHLEY, OF BROOKLYN, NEW YORK

FOUNTAIN PEN

Application filed January 16, 1929. Serial No. 332,863.

My invention relates to fountain pens.

The object of my invention is to provide a fountain pen which may be filled by the use of the cap portion of the pen.

5 A further object is to provide a pen construction which is free from threaded joints.

A further object is to provide a clip which is used as a part of a valve construction and operated in the act of filling the pen, in one 10 form of construction herein set forth.

Referring to the drawings which form a part of this specification,

Fig. 1 is a longitudinal sectional view of a pen embodying my invention and illustrating a construction in which the sack constitutes practically the entire reservoir for ink, and in which the clip is used as a valve in the filling operation.

Fig. 2 is a longitudinal sectional view of another or modified form of construction, in which the clip is not used in the filling operation, and in which the reservoir for ink is formed partly within the casing and partly within the sack portions of the pen.

25 Fig. 3 is a cross sectional view taken on line 3—3 of Figure 2.

Fig. 4 is a plan view of the top end of the clip.

Fig. 5 is a view of the stamped blank prior 30 to being bent into its finished form, as illustrated in Figure 1.

A—indicates the pen section and B—the outer casing which is secured thereto by a friction joint at C—in the usual manner.

35 D—indicates a feed-plug constructed with the usual feed-duct D'—leading to the reservoir E.

F—indicates a small tube connected to the feed plug and in open communication with 40 the feed-duct therein by a restricted passage E'.

G—indicates the pen point which is held in the usual way between the pen section and feed-plug.

45 H—indicates the cap of the pen, and is provided with the usual cylindrical plug I—the exposed end of which is adapted to abut the end I'—of the pen section in the usual manner.

50 The cap H— is made long enough to slide

slightly beyond the middle portion of the pen casing, said casing being increased very slightly in diameter at its middle portion so that the cap will be held by friction to the casing when used to cap the pen point. 55 Should the cap be made shorter, it should be made to frictionally engage the casing when used as a cap for the pen, but it is not necessary that it should be a tight friction fit when placed over the casing from the back end of 60 the casing as shown; the cap should fit the outer casing in easy air tight sliding relation therewith, to act to compress air within the casing to deflate the sack on the inward stroke of the cap in the filling operation. 65

The cap is provided with a small hole J—located as shown, and this hole may be closed by a finger of the hand in the filling operation, as constructed in Figure 2, or may be closed by pressing the ball end of the clip 70 K—over the hole during said operation. The clip K— is made to swivel on the cap projection H'— and to be held in any desired position by the nut L— which is screwed onto said projection after being inserted in 75 the space formed in the clip between the portions L'— and L², as will be readily understood.

The clip is made of spring metal and bends at the portion L²— thus providing a clip 80 which is short in length from the top to the ball shaped end, and yet gives a wide movement in bending at the point L²— so that a stiffer and stronger clip may be provided due to its increased effective length, as will be 85 readily understood.

The principal reason for the use of the clip in the filling operation is to prevent any ink from soiling the finger, which might occur if 90 ink should leak thru the hole J.

A more important reason for positioning the ball of the clip over the hole is, that in placing the cap onto the rear end of the pen when about to write, a finger may accidentally cover the hole and thus cause air to be compressed in the casing and expel ink from the reservoir. 95

Therefore, where I do not use the clip in the filling operation, I make a number of 100 holes J— spaced around the circumference

of the cap adjacent the element I—to prevent such an accident, but this construction requires all of said holes to be closed by the fingers in filling the pen, and this is not so desirable.

5 The use of the central air tube in pen construction is old and well known in the art, and needs no special description.

In Figure 2, the sack is made shorter in 10 length than that of the construction shown in Figure 1, and in order to fill the construction shown in Figure 2, two strokes of the cap filler is required, whereas, in Figure 1, a single stroke is sufficient if the cap is made as 15 long in proportion as illustrated in the drawings, and in this event, no inner tube is necessary. Where the reservoir is large, and the cap is made short in length, a number of strokes will be necessary to fill the reservoir.

20 In filling the reservoir, the pen section is inserted in the ink receptacle below the surface of the ink therein, and after closing the hole J—in the cap, the cap is forced over the casing, thus trapping air in the cap and forcing it into the casing to collapse the sack, and 25 on the outward stroke of the cap, the air is rarefied and ink drawn into the reservoir as the sack expands. On the second inward stroke of the cap, the air above the surface 30 of the ink in the reservoir, is forced out thru the air tube F—when the sack is deflated, a portion of the ink being trapped in the reservoir, and on the next expansion of the sack, due to its resilience, the reservoir will draw 35 a further supply of ink into the reservoir, as will be readily understood.

This construction may be provided at a low cost, and may be made of any desired material commonly used in making fountain pens.

40 Having thus described my invention, I claim as new:

1. A fountain pen comprising a casing having a hole at the end, a sack therein, a cap 45 adapted to cap the pen and also fitted to slide over the casing to deflate the sack in the act of filling the pen, said cap having a hole therein, a clip for said cap the free end of which is located over said hole and adapted to close the same.

50 2. A fountain pen comprising a casing having a hole at the end and a pen section, a feed plug in said section, a rubber sack, a cap adapted to cap the pen and also fitted to slide 55 over the casing in direct contact therewith to deflate the sack in the act of filling the pen; a cylindrical plug in the closed end of the cap, the one end of which serves as an abutment for limiting mounting movement 60 of the cap on the casing and pen section, and said cap having a hole in its side wall adjacent to and outwardly of said abutment, and means carried by the cap for manually closing said hole.

65 3. As stated in claim 2; and an air escape

tube extending from said feed plug to the back end of said sack.

4. A fountain pen comprising a casing having a hole at one end, a sack therein, a cap adapted to slide over the casing to near the 70 middle thereof to cap the pen, and adapted to slide over the casing in direct contact therewith to deflate the sack in the act of filling the pen, and means carried by the cap adapted to abut the end of the pen section, said cap 75 having a hole in its side adjacent the end of said means.

5. As stated in claim 4; and a spring clip carried by the cap to close said hole in its side.

In testimony whereof I have affixed my signature.

FRANK M. ASHLEY.
